UNITED STATES PATENT OFFICE.

JOSEPH LAWRENCE ORR, OF LEXINGTON, NORTH CAROLINA.

COMBINED ADVERTISING DEVICE AND TWINE HOLDER.

Application filed July 21, 1921. Serial No. 486,561.

To all whom it may concern:

Be it known that I, JOSEPH LAWRENCE ORR, a citizen of the United States, residing at Lexington, in the county of Davidson and State of North Carolina, have invented certain new and useful Improvements in Combined Advertising Devices and Twine Holders; and I do declare the following to be a full, clear, and exact description of the invention, such as will enable others skilled in the art to which it appertains to make and use the same.

My invention relates to improvements in twine holding devices for use in numerous kinds of stores and has reference more particularly to devices of this character intended for displaying advertising matter conspicuously and directing attention thereto whenever the twine is used.

20 The object of the invention is to provide an extremely simple and inexpensive, yet a highly efficient and desirable device of the class set forth, which is provided with a great number of advertising spaces so that 25 at least one advertisement can be seen regardless of the direction from which the device is viewed.

With the foregoing in view, the invention resides in the novel subject matter hereinabove described and claimed and shown in the accompanying drawings.

Figure 1 is a side elevation, partly in section, showing a device constructed in accordance with my invention.

35 Figure 2 is a vertical transverse sectional view as indicated by line 2—2 of Fig. 1.

Figure 3 is a top plan view.

Figure 4 is a horizontal sectional view as indicated by line 4—4 of Fig. 1.

40 Figure 5 is a top plan view of the strip of metal which carries the twine tensioning device to be described.

In the drawings above briefly described, the numeral 1 designates a vertically disposed rectangular frame having upstanding side boards 2, a horizontal upper end board 3 and a similar lower end board 4, all of said boards, 2, 3 and 4 being preferably of ornamental outline, substantially as shown. The 45 lower faces of the boards 3 and 4 and both faces of the side boards 2 are adapted to display advertising matter and hence when the frame 1 is suspended near the ceiling of the store, by any preferred means 5, at least 50 one of the advertisements may be seen, re-

gardless of the direction from which the device is viewed.

Extending between the boards 3 and 4 and positioned at the inner side of one of the side boards 2, are two vertical guide wires 6 which are preferably bent from a single length of wire as shown clearly in Fig. 2. The upper ends of the wires 6 are preferably provided with nuts 7 for drawing them to the desired degree of tightness. Slidably mounted upon the wires 6, preferably by having guide eyes 8 receiving said wires, is a vertically movable weight 9, whose upper end is provided with a twine-guiding eye 10. Above the eye 10, the top board 3 is provided with an opening 11, while at a point adjacent said opening 11, another opening 12 is formed through said board. The twine 13 is adapted to pass upwardly through the opening 12, to be looped downwardly 70 through the opening 11 and passed through the eye 10, and to then pass through guide eyes 14 at one of the upper corners of the frame 1. From these guide eyes, the twine is adapted to depend to the counter and if 75 desired another eye 15 may be provided at one of the lower corners of the frame.

From the construction so far described, it will be seen that each time the twine is pulled, preparatory to wrapping a bundle, the weight 9 will be raised and that when the twine is broken, said weight will drop and raise the twine above the counter. I make use of this movement of the weight 9 to operate an audible signal so as to attract 80 attention to the advertising matter displayed by the frame 1.

In the present showing, I have mounted a gong 16 on the side board 2 adjacent the weight 9 and have pivoted a clapper 17 to 85 said side board in position to be struck by one of the eyes 8, which eye is of greater size than the others as seen fully in Figs. 2 and 4. By this arrangement, each time the weight 9 is pulled upwardly, the gong 16 is 90 sounded and the patron's attention is directed to the advertising matter on the frame 1. Similarly, when the weight 9 is again dropped the gong is again sounded to further direct attention to the advertising 95 matter, thereby making the device an unusually effective advertising medium, particularly when it is borne in mind that the advertisement may be viewed from numerous angles.

Any suitable means may be provided on the lower end board 4 for holding the ball or roll of twine, and I have here shown a post 18 for this purpose. Similarly, numerous forms of twine-tensioning devices may be employed. I prefer, however, to secure a flat metal strip 19 upon the upper face of the top board 3, to provide this strip with openings alined with the openings 11 and 12, so that the twine may pass therethrough as shown in Fig. 1 and to mount a pivoted, gravity-lowered drag or tensioning device 20 on the inner end of said strip. This tensioning device is preferably of the construction shown, being formed from a single strip of metal with one end 21 bent upon itself around an appropriate weight 22, the other end of said strip being bent upon itself at 23 around a staple 24 which forms a pivot therefor. After the bend 23 is made the strip is bent in the opposite direction upon itself and extended to form a thumb-piece 25 normally inclined as seen in Fig. 1. When threading the twine 13 upwardly through the opening 12, the thumb-piece 25 is depressed so that the tensioning device 20 is moved to an out of the way position.

Since excellent results may be obtained from the details shown, they are preferably followed. It is to be understood, however, that within the scope of the invention as claimed, numerous minor changes may be made.

I claim:

1. A twine holder comprising a substantially rectangular vertically disposed open-ended frame work, means for carrying a bundle of twine thereon, a pair of vertically disposed wires extending between the top and bottom of said frame, a weight, eyes upon opposite sides of said weight and adapted to slidably pass up and down on said wires, an arm carried by said weight, a signal carried by said frame work and disposed adjacent the vertical pathway of

the weight, and means whereby the weight will be raised and lowered upon withdrawal of twine from the frame and the signal operated.

2. A twine holder comprising a frame equipped with twine holding means and a vertically movable weight, said frame having an upper end member provided with openings above said holding means and weight, the twine being adapted to be passed upwardly through the opening over the twine holder and to be looped downwardly through the other opening and engaged with said weight, a twine tensioning strip pivotally mounted and extending longitudinally of said upper end member and having its free end in twine engaging position, the pivoted end of the tensioning strip being provided with a handle extension permitting movement of the tensioning strip to an inoperative position, and a twine guide adjacent the opening above the weight.

3. In a structure of the character described, a frame, guide means disposed vertically in said frame, a twine holding element, a weight slidably carried by said guide means for movement vertically of the frame, a signal bell, a hammer for said bell pivotally mounted, abutment means extending from said weight to engage said hammer and move the same for striking the bell, and twine guiding means carried by said frame, said weight being provided with a twine-receiving eye whereby twine may be led from the twine carrier in engagement with the twine guiding means of the frame with a portion of the twine carried downwardly of the weight mounting means and slidably engaged with the eye of the weight and cause the weight to be moved vertically and impart movement to the hammer.

In testimony whereof I have hereunto set my hand.

JOSEPH L. ORR.
